(57) **CLAIM**

The ornamental design for a watchcase with leaf spring, as shown and described.

DESCRIPTION

FIG. 1 is a rear view of the watchcase with leaf spring showing our new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a right side view of the watchcase with leaf spring in open condition; and,

FIG. 8 is a rear perspective view of the watchcase with leaf spring shown in an open condition.

The broken lines are for illustrative purposes only and form no part of the claimed design.
